UNITED STATES PATENT OFFICE

JAMES ROBINSON, OF LONDON, ENGLAND

THERMIONIC VALVE

Application filed July 6, 1927, Serial No. 203,783, and in Great Britain November 30, 1926.

This invention relates to thermionic valves having a single cathode or filament, one or more control electrodes or grids and one or more plate electrodes or anodes.

- 5 According to the invention such valves are provided inside their envelopes with additional juxtaposed elements of similar physical character to the anode or grid, which are herein called grid elements and anode 55 elements because one or other of these elements, but not both of them, may be an extension of or directly connected with the grid or anode of the valve, and such connection is the only permanent connection with- 60 10 elements between these additional elements and any of the valve elements. Further, these elements are, by means other than screening, placed effectively or substantially outside the cathode field, that is to say there 65 15 is no flow or comparatively little flow of electrons from the filament through the grid element to the anode element, with the result that these juxtaposed elements fulfill only one of the functions of a valve grid 70 20 and anode, viz. by their capacity they allow high frequency effects to pass between the anode and the grid circuits. When the anode element or the grid element is an extension 75 25 of the valve anode or grid respectively, only 80 that part of the element which is outside the electron stream constitutes the anode element or the grid element, as the case may be, in the sense in which these terms are 85 30 herein used.

- 35 These additional grid and anode elements are of the same physical character as the grid or anode of the valve, that is to say they have extended metallic surfaces which in their juxtaposed position constitute a con- 90 denser having a capacity of the same order 95 as the grid-anode capacity of the valve, and when it is desired to have these capacities exactly equal, the additional grid and anode elements are made physical duplicates of the 100 valve grid and anode.

Such thermionic valves in one form or another are of utility as current amplifiers or as frequency multipliers, or for balancing out disturbances due to irregularities or changes of emission such as are obtained

when the filament is heated by alternating current. In the latter case the extra anode and extra grid, if employed, need not be used for the high frequency or low frequency wireless effects, but will be used to obtain an anode current which varies with the emission from the filament. This varying anode current in the second anode can now be employed to counteract variations of anode current from the first anode; or again, it may be used to vary the potential of the grid so as to keep the anode current in the first anode independent of variations of emission.

The subdivision and arrangement of the 65 elements of the various types of valves contemplated are illustrated diagrammatically in Figs. 1 to 4 of the accompanying drawing, while Figs. 5 and 6 illustrate also diagrammatically two constructions of valves of the 70 type shown in Fig. 1; Fig. 7 illustrates the application of such a valve to high frequency amplification; Fig. 8, a modified arrangement having the same object.

The valves shown in Fig. 7 have their 75 elements arranged in the manner shown in Fig. 1, while the valve shown in Fig. 8 is of the kind illustrated in Fig. 2.

In the type of valve shown in Fig. 1, the anode is subdivided while the grid is undivided. The two portions A, A' of the anode may be identical, but are not necessarily so.

In Fig. 2 the grid is subdivided, while the anode is undivided. As shown, the grid is divided into two portions G and G' and these portions may be identical in each case, or are unequal. The filament F may be asymmetrically disposed with respect to the grid and anode.

In Figs. 3 and 4 both the anode and the grid are subdivided. These subdivisions may be equal and symmetrically disposed with respect to each other, but are not necessarily so.

The anode portions may be cylinders A, A' placed end to end as shown in Fig. 5, or side by side as shown in Fig. 6, and separated from each other so that there is no direct electrical conduction between them,

and the filament F may be co-terminous with one cylinder, while the coil-shaped grid G, which in Fig. 6 is shown as being in two conductively connected parts, extends along the entire length of both cylinders, which may be equal and symmetrically disposed with respect to the grid. Instead of having a double or divided anode and a single grid, there may be a double or divided grid and two anodes or a single anode extending along the length of both grids, the filament being co-terminous with one grid only or with both.

Obviously more than one of such special valves can be combined in one container. In this case the filaments can be arranged to be in series or in parallel; for example, a convenient unit is two such special valve elements and one ordinary three-electrode element to act as a rectifier inside one glass envelope.

Valves constructed in accordance with the present invention may be employed, e. g., for high frequency or low frequency amplification, and Fig. 7 illustrates diagrammatically the use of two such valves for two-stage high frequency amplification.

As shown, capacity coupling is used between the two valves, but inductive coupling can be substituted. It will be seen that the two portions of the anode A, A' in each of the valves V, V' are connected with the ends of the anode inductance coil I, which is preferably tuned by a shunting condenser C. Preferably also the high tension battery is connected with the divided anode through a central or variable tapping point X on the anode inductance coil I. In this case it will be noted that only one portion of the anode, namely A, is in the effective field of the grid and filament, the latter being co-terminous with the anode A.

Fig. 8 shows diagrammatically a construction of valve in which the grid is divided into two parts G, G', while the anode A which is co-extensive with the two grids is undivided, the filament F being co-terminous with one part of the divided grid, namely part G. The two parts of the divided grid are connected directly with the ends of the grid coil K which is tuned by means of variable condenser C shunting the ends of the grid coil. A tapping Y (which may be central or adjustable) on the grid coil K is joined to filament F through any potential device required, as for example a battery and potentiometer.

These special valves may be combined for different purposes in various ways with each other, or with ordinary three-electrode valves. For instance, three valves such as shown in Fig. 8 may be used for three-stage high frequency amplification followed by an ordinary three-electrode valve acting as a detector and oscillator, that is to say this

last valve can employ reaction, and after this valve as many stages of low frequency amplification can be used as required. In such an arrangement there may be reaction on one of the valves without any fear of radiation consequent on such reaction, and therefore without any danger of disturbance to other receiving circuits.

It will be understood that the valves hereinbefore described can be utilized for radio transmission as well as for radio reception.

Having thus described the nature of the said invention and the best means I know of carrying the same into practical effect, I claim:

1. A thermionic valve having a single filament, a control electrode and plate electrode and a plurality of additional juxtaposed elements of similar physical character to the said electrodes and disposed substantially outside the cathode field, the filament being asymmetrically disposed with respect to the valve electrodes and the additional juxtaposed elements.

2. A thermionic valve according to claim 1, wherein the additional juxtaposed elements have substantially the same reactance to high frequency currents as the grid anode capacity of the valve.

3. A thermionic valve having a single filament, wherein besides the control and plate electrodes of the valve there are provided inside the envelope additional juxtaposed elements of similar physical character to the said electrodes of the valve, one of which additional elements, but not both, being directly connected with one of the said electrodes of the valves, such connection being the only permanent connection within the valve between these additional elements and any of the valve electrodes and these additional elements being located substantially outside the cathode field.

4. A thermionic valve according to claim 1, wherein the additional juxtaposed elements are placed effectively outside the cathode field by an appropriate asymmetrical disposition of the cathode with respect to the valve elements and the additional juxtaposed elements.

In witness whereof I have signed my name to this specification.

JAMES ROBINSON.
